UNITED STATES PATENT OFFICE.

CHARLES F. SPEIDEL AND JOHN CHRISTIE, OF ROCHESTER, NEW YORK, ASSIGNEES
TO EASTMAN KODAK COMPANY, OF ROCHESTER, NEW YORK, A CORPORATION OF
NEW YORK.

NUMBERING STAMP FOR PHOTOGRAPHIC-PRINTING MACHINES.

Application filed February 10, 1923. Serial No. 618,379.

To all whom it may concern:

Be it known that we, CHARLES F. SPEIDEL and JOHN CHRISTIE, citizens of the United States of America, residing at Rochester, 5 in the county of Monroe and State of New York, have invented certain new and useful Improvements in Numbering Stamps for Photographic-Printing Machines, of which the following is a full, clear, and exact specification.

This invention relates to photography having particular reference to the numbering stamps used as a part of the complete photographic printing machine. It has for 15 its object to provide a metallic numbering stamp which is sufficiently resilient in its action to work successfully upon a printing machine. Another object is to provide a resilient mounting for the stamp, and to 20 provide a mount upon which the entire stamp may be swung so that an operator may view the type when necessary. A further object is to provide a combined rigid and resilient type member so that each 25 member is individually resilient. A further object is to provide a convenient number changing mechanism. Other objects will appear hereinafter from the following specification, the novel features being 30 pointed out in the claims at the end of the specification.

The problem of providing a suitable numbering stamp for a photographic printing machine is much more difficult than that of 35 providing a satisfactory disk stamp because of the conditions under which it is used. For a printing machine the stamp is usually mounted on the top of a platen which has a paper contacting face which is compressible, thus the distance from the top to 40 the bottom of the platen varies through wide limits, obviously increasing the difficulty of mounting a stamp in position to give good contact. The stamp must function 45 on the back of a sheet of photographically sensitized paper, the emulsion side of which is highly sensitive to pressure so that too great pressure on the stamp may cause "pressure markings" on the developed print. 50 Moreover, as the printing paper and negative lie upon a glass printing panel undue pressure may also injure the glass. The printing paper varies in thickness within wide limits and the negative may be on

thin or thick film or upon a glass plate, and 55 as one or more masks may also be used, the total thickness of the pile upon the top of which the stamp prints its legend may also vary considerably.

With all these variables it is necessary to 60 secure a firm but light contact to secure legible printing which does not in any way injure or dent the paper and mar the resulting print. Flexible rubber type works 65 satisfactorily where proper contact can be secured, but the life of such type is short and requires constant replacements, and its resiliency makes it difficult to retain accuracy of dimensions for any length of time. We have provided a stamp made chiefly of 70 rigid materials at the wearing points and yet having resilient qualities due to construction, as will be hereinafter fully described.

In the drawings in which like reference 75 characters denote like parts throughout:

Fig. 1 is a perspective view of a printing stamp constructed in accordance with and illustrating one embodiment of my invention; being shown in proper relation to 80 parts of a printing machine;

Fig. 2 is a plan view of the stamp and mount;

Fig. 3 is a section on line III—III of 85 Fig. 2;

Fig. 4 is a section on line IV—IV of Fig. 2; and

Fig. 5 is a detail side elevation of one of the type disks.

In the drawing we have shown only a portion 90 of a photographic printing machine, illustrating such parts as will be necessary for an understanding of the application of our invention to a printer. The stamp 1 is mounted upon a hinged member 2, having 95 one section 3 fastened to the platen 4 of the machine. In this case the platen 4 is carried on each side by a pair of parallel links 5, 5 pivoted to the platen at 6, 6 and to a support 7 at 8, 8. Support 7 is fastened to the 100 cabinet 9, which carries the usual glass printing panel 10 under which there is the usual printing and pilot lamps which are not shown. The platen 4 is moved upon links 5, 5 parallel to the printing panel 10 by 105 means of an operating handle 11, connected to side arms 12 (one shown) each of which is slotted at 13 to receive a pin 14 carried by

platens 4; so that the leverage on handle 11 is increased as the platen approaches panel 10. Each arm is pivoted at 15 to support 7, so that by drawing handle 11 forward the platen is lowered upon the paper P on the printing panel 10. In this instance platen 4 is provided with a plate 16 faced with felt 17, the plate being spring pressed from platen 4, these parts being to assist in obtaining 10 a firm and even pressure on the paper P.

The printing stamp 1 consists of preferably a die cast casing 18 having lugs 19 extending to the sides, apertured at 20. Pins 21 carried by the hinged member 2 pass 15 through these apertures and are encircled by springs 23. As the base 24 extends through the opening 25 of member 2, it can be seen that springs 23 tend to retain the lugs 19 against plate 2, but they permit the 20 casing to move a limited distance from it and also allow for a rocking movement, as it is, of course, possible to compress one spring more than the other. Thus the casing is resiliently carried by hinged member 2.

A shaft 26 extends between the sides 24, 24 forming the base of the casing. This shaft supports a plurality of type disks 27, here shown as four. These disks are equipped with the usual characters 28 on 30 their peripheries, and with the usual moving ratchet 29. Our invention includes the structure used to resiliently mount these disks, that is, interposing an annular resilient member 30, preferably rubber, between the annular character bearing disk 27 and the annular bearing member 31 which slides on shaft 26.

A series of latches 32 on shaft 33 contact 40 with the moving ratchets 29, under the impulse of spring fingers 34. This structure is well known. The disks are moved by a yoke 35 having side arms 36 mounted on shaft 26, and carrying a ratchet engaging latch bar 37 pressed toward ratchets 29 45 by spring 38. This bar carries a series of pawls 39, 39', 39'', 39''' of progressively shorter lengths to successively engage ratchets 29 in the well known manner, causing the number to advance by one at each movement of 50 the yoke 35. A coiled spring 40 (Fig. 3) normally holds the yoke in the position shown in full lines, Fig. 4.

The front part 41 of the casing 18 is provided with a bearing 42, in which there slides 55 a plunger 43 with a finger portion 44 on the upper end, and a knob 44' on the lower end, the direction of movement of this rod being at substantially right angles to shaft 26. Knob 44' engages a crossbar 45' on the yoke 35; and by depressing finger portion 44 60 the yoke is moved, thus changing the numeral made by the characters 28.

The hinged member 2 carrying the numbering stamp is connected to part 3 by a 65 pintle 45, about which there are coiled

springs 46 tending to hold member 2 against the platen 4 in a position in which the opening 25 practically registers with a similar opening in the platen through which the stamp operates. A turn buckle 47 is for holding member 2 against the platen. When an operator desires to see the characters, member 2 is unlatched and swung against the action of springs 46. This is a useful feature for setting the stamp to a desired 75 number, cleaning, etc. When platen 4 is in its inoperative position—Fig. 1—the type 28 rest upon an inking pad supported by a bracket 50.

Springs 23 tend to properly position the 80 stamp casing as a whole with respect to the paper, which may vary considerably in thickness, and the flexible annular members 30 insure each individual type carrying member being brought into firm contact with the paper so that a numeral M may be 85 printed thereon without undue pressure or marring the sensitive paper.

Having thus described our invention, what we claim as new and desire to secure 90 by Letters Patent is:

1. In a photographic printing machine, the combination with a platen adapted to move to and from an operative position in contact with a sheet of printing paper, of a printing stamp, and a hinged carrier for the printing stamp attached to the platen, said printing stamp being mounted upon the hinged carrier. 95

2. A device as called for in claim 1 in which the hinged carrier is spring held against the platen. 100

3. A device as called for in claim 1 in which the hinged carrier may be latched against the platen. 105

4. In a photographic printing machine, the combination with a platen adapted to move to and from an operative position in contact with a sheet of printing paper, of a printing stamp comprising a rigid casing, a resilient mounting between said casing and said platen, rigid type carrying members mounted in said casing, the resilient mounting between the casing and the platen permitting movement of the former with respect to the latter as the latter is lowered upon the printing paper. 110

5. In a photographic printing machine, the combination with an apertured platen adapted to move to and from an operative position in contact with a sheet of paper, of a printing stamp, and a hinge having a pintle, one part of the hinge carrying the printing stamp and the other part being affixed to the platen of the machine, printing characters carried by the stamp extending into the aperture of the platen, the printing characters being exposed to view by swinging the stamp mounted on a part of the hinge about the hinge pintle. 120 125 130

6. In a photographic printing machine, the combination with an apertured platen adapted to move to and from an operative position in contact with a sheet of paper, of an apertured carrier hinged to the platen and a printing stamp supported by the hinged carrier being adapted to extend through the apertures in the platen and carrier, whereby a part of the stamp will contact with the paper together with the platen. 45
7. An apparatus as called for in claim 6 in which the stamp is supported upon the carrier by means of springs which permit a limited rocking movement in all directions. 50
8. In a photographic printing machine, the combination with a platen adapted to be moved into contact with a sheet of paper at one extent of its movement, of a printing stamp casing resiliently mounted thereon, rigid type carrying members carried by the stamp casing, a resilient mount for each type carrying member for supporting it in the stamp, the resilient mounting of the stamp casing aligning this part properly when the platen is lowered into contact with the paper, and the individual resilient mounts for the type carrying members properly aligning the printing members whereby firm and even contact between the type carrying members and the paper is insured. 55
9. In a printing stamp, the combination with a rigid rotatable annular member carrying characters around its periphery, of a shaft for supporting said member, and a resilient annular member located between the rigid annular member and the shaft. 60
- 40 10. In a printing stamp, the combination with a type carrying disk comprising a rigid annular member, of a core for said member composed of non-rigid material, a bearing for the non-rigid member comprising a rigid annular member with an aperture in the center thereof, and a shaft for supporting the type disk, said shaft being adapted to pass through the aperture in the bearing. 65
11. In a printing stamp the combination with a casing, a shaft supported thereby, a plurality of type bearing members carried by the shaft, each type bearing member being of rigid material, and having a resilient band of material between the type bearing member and the supporting shaft, whereby each of the type bearing members is individually movable to a limited degree. 70
12. A type disk for printing stamps including a metallic annular type bearing member supported in its entirety by an annular rubber member. 75
13. A type disk for printing stamps comprising an annular metallic type carrying member, an annular metallic supporting member separated by an annular rubber member, permitting limited movement of one metallic part relative to the other. 80
14. In a printing stamp, the combination with a stamp casing, lugs extending from the casing, a support, pin and aperture connections between the lugs and the support, and springs surrounding the pins exerting a pressure normally tending to hold the printing stamp casing to the support, but permitting a rocking movement of the casing relative to the support. 85

Signed at Rochester, New York, this 7th day of February, 1923.

CHARLES F. SPEIDEL.
